UNITED STATES PATENT OFFICE.

GEORGE L. WADSWORTH, OF BROOKLYN, NEW YORK.

NECKTIE-HOLDER.

995,741.

Specification of Letters Patent. Patented June 20, 1911.

Application filed April 17, 1911. Serial No. 621,544.

To all whom it may concern:

Be it known that I, GEORGE L. WADSWORTH, a citizen of the United States, residing in the borough of Brooklyn, county 5 of Kings, and State of New York, have invented new and useful Improvements in Necktie-Holders, of which the following is a specification.

This invention relates to neck-tie holders 10 of the type shown, and has for its particular objects the provision of a unitary device which is adapted to securely retain either cravats or bow ties, and yet permit of the ready removal of the same as required for 15 use. In many of the constructions of this general type as heretofore provided, it has been customary to provide pegs or rings for the reception of the ties. The former, while permitting of the convenient application 20 and removal of a tie therefrom, are unsatisfactory in that they do not positively retain the tie against displacement. The latter, on the other hand, have exactly the opposite function since while the displacement of the 25 ties is adequately prevented, yet in order to apply or remove the ties they must be laboriously threaded through, or drawn from, said rings.

The aforesaid objectionable features are 30 overcome by my present construction, the same being fully set forth and described in the accompanying specification and drawings forming a part thereof, in which—

Figure 1 is a front elevation of my improved neck-tie rack, showing the tie in position thereon; Fig. 2 is an end elevation of said rack bar; and Fig. 3 is a perspective view of the framework isolated.

Referring to the drawings and the construction shown therein, the reference letter A designates a rack, which may be suspended if desired, the same being preferably constructed of wood, although obviously any other suitable material may be employed, 45 said rack consisting of an upper portion 1 and over-lapping bottom 2, which is secured thereto by means of screws, or other retaining means, 3. The upper portion 1 of said rack is provided with oppositely disposed 50 longitudinally extending grooves or channels 4, positioned intermediate lateral longitudinal ribs 5, 5 and shoulders 6, 6 at the bottom of said upper portion 1 of said rack bar.

55 A framework comprising vertical loops 8 and transverse feet 9, 9' envelops the bot-

tom and sides of the upper portion 1 of said rack, being secured thereto by means of the lower overlapping portion 2. Preferably, said framework is formed from a single 60 piece of spring-steel wire in order to obtain a rigid unitary support for the elastic fingers or loops 8. The feet of said framework are preferably arranged as shown in pairs 9, 9 and 9', 9', respectively, both members of a particular pair which forms the foot of a rear loop converging from front to rear toward each other, and diverging with respect to an adjacent member of a pair which forms the foot of the next succeeding 70 loop.

The top of the upper portion 1 is preferably beveled to form a ridge 10 and supplemental channels 11, 11 intermediate the ribs 5, 5 and said ridge. This configuration results in the loops or fingers 8, extending above and out of contact with the top of the upper portion 1 of said rack and permits of the convenient application when desired of the neck band of a tie around said fingers or 80 loops.

It is evident from the construction above described, that the vertical loops or fingers 7 will project across the recesses 4, and lightly contact with or bear against the ridges or ribs 85 5. The wire from which said loops are formed is of spring metal in order to maintain the same in contact with the said shoulder 5, while permitting of the same being retracted to a sufficient distance to permit of the application to said loops of a neck-tie C, either 90 cravat or bow-tie as desired. Thereby it is merely necessary to grip the upper end of said loops with the thumb and forefinger and force the same outwardly to a sufficient 95 distance to permit of the application of the said tie.

The convenience of such a construction as that hereinabove described is apparent and the same is admirably suited for preserving the 100 ties in an orderly and neat arrangement. Moreover, the same can be either suspended from a rod or loop, or if desired allowed to lie flat with one of the sides in contact with a supporting surface as the bottom of a 105 drawer of a dresser or the like.

Having thus described my invention, what I claim and desire to secure by Letters Patent is:—

1. A neck-tie holder comprising a support 110 having a lateral longitudinal extending rib, provided with a lateral longitudinal

main channel formed intermediate the bottom of said support and said rib, a skeleton framework secured to the bottom of said support, said framework being formed into 5 a plurality of successive fingers which project from the bottom of said support across said channel and into proximity to said rib.

2. A neck-tie holder comprising a support having oppositely disposed lateral longitudinal ribs positioned intermediate the top and bottom respectively of said support, a longitudinal ridge extending along the top of said support, oppositely disposed lateral longitudinally extending main channels 10 respectively positioned intermediate said ribs and bottom of said support, oppositely disposed supplemental channels positioned intermediate said ridge and said ribs, a skeleton framework formed of a single 15 piece of spring-steel wire secured to the bottom of said support, said framework being provided with oppositely extending fingers 20

which extend from the bottom of said support across said main channels and into proximity to said ribs, and means secured to 25 said support and enveloping the lower end thereof for concealing said framework.

3. A neck-tie holder comprising a support provided with a lateral longitudinal main channel, a skeleton framework of 30 spring-steel wire provided with a plurality of elastic clips which are arranged to span said channel and extend in sufficiently close proximity to said support to prevent accidental displacement of a tie positioned in 35 said channel.

In witness whereof I have hereunto set my hand at the city of New York, county of New York and State of New York, this 15th day of April, 1911.

GEORGE L. WADSWORTH.
